UNITED STATES PATENT OFFICE.

JOHN M. PETERSON, OF CHICAGO, ILLINOIS, ASSIGNOR TO GEORGE J. SAYER, OF CHICAGO, ILLINOIS.

SLICING-MACHINE.

1,243,867.

Specification of Letters Patent. Patented Oct. 23, 1917.

Application filed June 12, 1916. Serial No. 103,122.

To all whom it may concern:

Be it known that I, JOHN M. PETERSON, a citizen of the United States, residing at Chicago, in the county of Cook and State 5 of Illinois, have invented a certain new and useful Improvement in Slicing-Machines, of which the following is a full, clear, concise, and exact description, reference being had to the accompanying drawings, forming 10 a part of this specification.

My invention relates to slicing machines, and more particularly to that kind of slicing machines for slicing such products as meats, and has for its object the provision 15 of an improved machine of this character.

One of the objects of my invention is the provision of a slicing machine with the setting mechanism so arranged that the thickness of slices can be readily adjusted by the 20 operator even during the process of slicing.

Another object of my invention is to provide improved means for feeding the meat table periodically after the severance of each slice, my invention furthermore 25 contemplating the construction of this portion of the apparatus in such a way that the feed screw commonly employed to perform this feeding function is substantially enclosed whereby it is permitted more readily 30 to maintain an oil surface and whereby the liability of rearrangement thereof is minimized; furthermore all danger of tampering with the feed screw or of accidents due to its exposure is thereby avoided.

35 I will explain one form of machine embodying a structure capable of performing the results and functions above outlined more in detail by referring to the accompanying drawings illustrating such machine, in which—

Figure 1 is a plan view of a machine constructed in accordance with my invention;

Fig. 2 is an end view of the machine illustrated in Fig. 1;

45 Fig. 3 is a detail sectional view along line *a—a* of Fig. 1;

Fig. 4 is a detail sectional view of a portion of the adjusting mechanism along line *b—b* of Fig. 1.

50 My improved slicing machine comprises the bed plate 1 which carries suitable guides or ways 2 and 3, upon which the meat table 4 is slidable. This meat table is actuated by the crank 5, and link 6, which link is pivot-

ally associated to the table in the well known 55 form, the crank 5 being suitably driven through the agency of the handle 7 mounted upon the customary fly wheel 8. The machine is further provided with a slicing 60 knife 9 having the meat tray 10 upon which the severed slices fall. The knife 9 is suitably carried within the housing 11, which housing carries the power transmitting mechanism for transmitting the power from the fly wheel 8 to the slicing knife or blade 65 9. The meat table 4 carries a meat plate 12 which meat plate is slidably mounted upon the meat table 4 in the customary way. A feed screw 13 is pivotally carried by the 70 meat table, being held in suitable bearings 14, 15. This feed screw is given periodic rotational actuation through the agency of the dog 16 as will presently appear. The feed screw 13 is adapted to be engaged by 75 a toothed element 17 which is carried by the meat plate 12. This toothed element 17 is movable into and out of engagement with the screw portion provided upon the feed screw 13. The mechanism for effecting this engagement and disengagement is more 80 clearly illustrated in Fig. 3.

In Fig. 3 I show the meat plate 12 as provided with an overhanging arm or housing 18, which housing has an extending cylindrical shell 19. A lever 20 is likewise pivotally secured to this housing, this lever 20 carrying at its lowermost extremity the toothed element 17 and carrying at its upper extremity an arm 21 which bears against the left hand extremity of a spring 22. This 90 spring 22 is adapted to exert pressure against the lever 20 tending to force the toothed element 17 tightly against the feed screw 13. A handle 23 carried upon the crank 24 is mounted upon the spindle 25, 95 which spindle carries at its lower extremity the cam 26 adapted to rotate the element 20 by pressing it against the action of the screw 28 when it is desired to release the element 17 from the feed screw 13. Thus a rotation 100 contra-clockwise of the handle 23 into its dotted position, as shown in Fig. 3, will press the cam 26 against the lever 20 so as to move said lever clockwise and thereby 105 rotate the toothed element 17 from engagement with the feed screw 13. Whenever it is desired to permit engagement between the toothed element 17 and the feed screw

13, the handle 23 is moved back to the position shown in Fig. 3 which is the same as the position shown in Fig. 1.

In order to keep the feed screw in properly oiled condition and to prevent it from accumulating dust and dirt I provide a shell 27 extending between the bearings 14 and 15, which shell securely covers and incloses the screw 13 except along that portion of the periphery of the screw where it is in engagement with the toothed element 17 as shown more clearly in Fig. 3, this shell 27 having a longitudinal slot to permit of the unobstructed movement of the tooth 17 longitudinally of said shell. Exposure of the feed screw is thus avoided and accidents resulting from contact therewith are thus likewise prevented.

In order to give a periodic rotational actuation to the feed screw 13 I provide a link 28 pivoted to the meat table 4, which link carries at its lower surface the cam or dog 16. This link is pivotally connected by means of a link 29 which suitably engages the ratchet construction, consisting of the ratchet wheel 29^a and ratchet 29^b shown more clearly in Fig. 5, provided within the housing 30 which moves the feed screw forward with each contra-clockwise movement (Fig. 2) of the link 28. The thickness of the slices depends upon the degree of movement of the feed screw 13 during each actuation, and this is controlled by the amount of movement of the dog 16 which in turn is controlled by the position of the roller 31. A handle 32 is fixedly secured to the screw 13 to rotate it to advance the meat plate 12 when so desired without operating the entire machine. The roller 31 is carried by a bolt 33 (Fig. 4) which at its left hand extremity is provided with a rack portion 34 engaging the pinion 35. A suitable housing 36 entirely incloses the bolt 33 and pinion 35. The thickness of the slice is dependent upon the degree of displacement of the roller 31 from the position it occupies in Fig. 4, and this roller may be moved outwardly from its innermost position by a rotation of the pinion 35. This rotation is secured through the agency of the handle 36, which handle actuates the shaft 37, this shaft being fixedly secured to the pinion 35.

It will be seen that the operator of the machine who usually stands at the upper right hand corner of the machine (Fig. 1) may operate the handle 7 and at the same time operate the handle 36 to control the thickness of the slices. The handle 36 has a spring pressed pin 38, which pin is adapted to coöperate with suitable holes or recesses 39 provided in a graduating dial 40 so that the operator by an inspection of the dial may know exactly the thickness of the slices which the machine is cutting. The great advantage of thus being able to adjust the

thickness as the machine is being operated will be readily apparent when it is borne in mind that the operator usually wants to see the severed slice before resetting and this can be done with the apparatus in the condition shown by the operator merely observing the slice as it is being cut. It is not necessary for the operator to sever a slice and then walk around to some other point of the machine in order to reset the mechanism which controls the thickness of the severed slice.

The resiliently pressed tooth piece forces the meat plate at one extremity thereof against its opposite vertical guide, and in addition the other extremity of said meat plate is forced against the said guide by the spring 41 which is carried in the slot 42 and held by the cap 43. Thus I obtain an even wear of the meat plate against the wearing guide.

From what has been described the nature of my invention will be more readily apparent to those skilled in the art.

Having however thus described one form which my invention may take, what I claim as new and desire to secure by Letters Patent is:

1. A machine of the character described in combination with a meat table, a feed screw carried thereby, a meat plate reciprocatingly mounted upon said meat table, a guide for said meat plate, and means carried by said meat table for detachably engaging said feed screw, said means including a spring pressed tooth piece, a spring tending to press said tooth piece against the side of said feed screw, thereby pressing said plate against its guide, and a manually actuated cam for actuating said tooth piece against the action of said spring to release it from said feed screws.

2. A machine of the character described in combination with a meat table, a feed screw carried thereby, a meat plate reciprocatingly mounted upon said meat table, a guide for said meat plate, means carried by said meat table for detachably engaging said feed screw, said means including a spring pressed tooth piece, a spring tending to press said tooth piece against the side of said feed screw, thereby pressing said plate against its guide, a manually actuated cam for actuating said tooth piece against the action of said spring to release it from said feed screw, and a stationary housing substantially inclosing said cam, spring and tooth piece.

3. A slicing machine of the character described comprising a movable meat plate, a slidable meat table upon which said meat plate is slidably mounted, a feed screw rotatably carried by said meat table for imparting periodic movement to said meat plate, bearings carried by said meat table for

said feed screw, an inclosing slotted stationary shell for said screw extending beyond said bearings, means fixedly carried by said meat plate and adapted to engage 5 said feed screw, a portion of said means extending through said slotted shell, an inclosing shell for said last aforesaid means, means carried by said meat table for imparting step by step motion to said feed screw,

and an inclosing shell for said last aforesaid means.

In witness whereof, I hereunto subscribe my name this 5th day of June, A. D., 1916.

JOHN M. PETERSON.
